ANIMAL FIGURE TOY

Gregory Lambert, 12-58 5th St.,
Fair Lawn, N.J. 07410

Filed Feb. 10, 1975, Ser. No. 548,461

Term of patent 14 years

Int. Cl. D21—01

U.S. Cl. D34—15 B

FIG. 1

FIG. 2

FIG. 3

FIG. 4

FIG. 5

FIG. 1 is a left side elevational view of an animal figure toy showing my new design, the side opposite being a mirror image thereof;

FIG. 2 is a front elevational view thereof;

FIG. 3 is a top plan view thereof;

FIG. 4 is a rear elevational view thereof; and

FIG. 5 is a bottom plan view thereof.

I claim:

The ornamental design for an animal figure toy, as shown and described.
